UNITED STATES PATENT OFFICE

123,681

DESIGN FOR A SYRINGE BAG OR SIMILAR ARTICLE

Earla M. Roberts, Lancaster, Pa., assignor to Armstrong Cork Company, Lancaster, Pa., a corporation of Pennsylvania

Application March 20, 1940, Serial No. 91,102

Term of patent 14 years

To all whom it may concern:

Be it known that I, Earla M. Roberts, a citizen of the United States, residing in Lancaster, county of Lancaster, and Commonwealth of Pennsylvania, have invented a new, original, and ornamental Design for Syringe Bags and Similar Articles, of which the following is a specification, reference being had to the accompanying drawing forming a part thereof, in which syringe bag or similar article embodying my new design.

The opposite side of the syringe bag from that shown in the drawing has substantially the same appearance as the side illustrated.

I claim:

The ornamental design for a syringe bag or similar article, substantially as shown and described.

EARLA M. ROBERTS.
